GUSTAV A. WIIG. Inventor

By Willard Eddy, Attorney

UNITED STATES PATENT OFFICE.

GUSTAV A. WIIG, OF OMAHA, NEBRASKA, ASSIGNOR TO ROBERT MARMET, OF OMAHA, NEBRASKA, AND HIMSELF.

FURNACE.

Application filed January 18, 1928. Serial No. 247,558.

My invention relates especially to that class of tubular hot air furnaces which are commonly used for heating dwellings and other buildings, and which individually comprise a combustion chamber, a housing which surrounds the combustion chamber, and a plurality of tortuous, or roundabout, flues for heating air in the housing. It is the main and comprehensive object of the invention 10 to increase the heating efficiency of such a furnace by transferring to the air within the housing as much as possible, or all, of the heat which is derived from the fuel consumed; and to increase the heating power of 15 the furnace without increasing its size. To accomplish these objects I incorporate in my improved furnace, as parts thereof within the housing, a combustion chamber of special description, a manifold united with that 20 chamber, a plurality of flues tapping the manifold, and a radiator connected with the flues.

In the accompanying drawings, illustrating the best manner in which I have contemplated applying the principles of the invention, Fig. 1 is a front elevation of a gas-burning furnace which is constructed in accordance with these principles. This elevation is partly in vertical section on the section line 1—1 of Fig. 5. Figures 2, 3 and 4 are details. Fig. 2 is a vertical section on the section line 2—2 of Fig. 5. Fig. 3 is a side elevation partly in vertical section on the section line 3—3 of Fig. 2. Fig. 4 is a vertical section on the section line 4—4 of Fig. 5. Fig. 5 is a side elevation of the same furnace, partly in vertical section on the section line 5—5 of Fig. 1, and partly broken away to show the contents of the combustion 40 chamber.

In these drawings the housing of the furnace is denoted by the numeral 1. It is a double-walled metallic shell, of general rectangular or cubical form, having in its opposite side walls and near the bottom thereof the air inlets 2, and having near the top of its side walls a plurality of air outlet pipes 3. It has also the front door 4 for access to a combustion chamber, the front door 5 for 50 the admission of air to a burner, and the rear outlet pipe 6 for connection with a chimney.

Between the vertical walls of this housing, and moderately spaced therefrom, the combustion chamber 7, including the burner 8 as 55 well as the passageways 9 and 9' for air to the

burner, is supported by the brackets 10. This chamber is a hollow metallic shell having the general external form of a polygonal prism and supported in a horizontal position in the air chamber 11 within the housing. It has 60 two duplicate upper walls 20 converging symmetrically from its narrow sides 23 to the top line of the combustion chamber like a ridge roof, and two duplicate under walls 21 similarly converging to its horizontal bottom 22. It is perforated from top to bottom by a plurality of tubular air passages 13, rectangular in cross section, and has a lining of firebricks 14 for the protection of the sides 21 near the burner 8. To increase the 70 radiating surface of the combustion chamber and to promote the distribution of its gaseous contents, its extreme right and left marginal portions adjacent to its side walls 23, and to the air passages 13, contain severally 75 a plurality of alined horizontal narrow tubular conduits 19, which form part of this chamber. Thus the air chamber 11 and the combustion chamber 7 mutually interpenetrate, the one by its air passages 13 and the other 80 by its flues 15, etc.; while separated parts of the combustion chamber are connected by the conduits 19. The chamber 7 is further provided with the upstanding manifold 12, which is a hollow metallic shell, or dome, 85 across the top of the combustion chamber near one end thereof and intercommunicating therewith. From the upper part of this manifold proceed symmetrically the separate flues 15 and 15, which are rectangular in 90 cross section, and which individually comprise descending portions thereof and lead circuitously in the air chamber 11 to the radiator 16. This radiator is a metallic shell having the general form of a short polygonal 95 prism whose sides are in the same planes respectively as are those of the combustion chamber. It has separated top inlets which are continuous with the flues 15 and 15 respectively and a rear outlet 17 which is continuous with the chimney pipe 6. It also contains the baffle plates 18 and 18, and is supported a short distance behind the combustion chamber by the bracket 10'. Operatively the hot gases of combustion circulating in an air chamber which is of comparatively small size, pursue the long, retarded, confined, compacted and heat-dispensing course which is indicated in the drawings by the feathered arrows.

I claim as my invention—

A furnace of the specified class, comprising a combustion chamber, a plurality of air passages extending vertically through the combustion chamber near each of its side walls, a manifold extending upward from the top of the combustion chamber, a radiator, a pair of flues, angular in cross section, leading cir-

cuitously and downward from the manifold to the radiator, and a housing forming an air chamber enclosing the combustion chamber, the manifold, the radiator and the flues.

Witness my signature at Omaha, Nebraska, January 7th, 1928.

GUSTAV A. WIIG.
